Louis Albert Samstag, New York, N. Y.

Application January 16, 1936, Serial No. 60,622

Term of patent 3½ years

To all whom it may concern:

Be it known that I, Louis Albert Samstag, a citizen of the United States, residing in New York, county and State of New York, have invented a new, original, and ornamental Design for a Lip Stick Holder, of which the following is a specification, reference being had to the accompanying drawing, forming part thereof:

Figure 1 is a top plan view of a lip stick holder showing my new design; and

The dominating feature of my design resides

in the combination with the cylindrical body member shown, of a surmounting ornamental ball-like member substantially greater in diameter than the cylindrical body member and projecting laterally thereof so that in plan view the cylindrical body member is obscured by said ball-like member.

I claim:

The ornamental design for a lip stick holder as shown and described.

LOUIS ALBERT SAMSTAG.
